TWIN TANDEM ENGINE AIRPLANE

Donald J. Ahrens, Wichita, Kans., assignor to The Cessna Aircraft Company, Wichita, Kans., a corporation of Kansas

Filed May 27, 1963, Ser. No. 75,075

Term of patent 14 years

(Cl. D71—1)

FIG. 6

FIG. 1 is a side elevational view of a twin tandem engine airplane embodying my new design;

FIG. 2 is a top plan view of the same;

FIG. 3 is a front elevational view of the same;

FIG. 4 is an enlarged scale fragmentary rear perspective view of a portion of the same airplane illustrating the aft end of the aft engine nacelle;

FIG. 5 is a rear elevational view of the same airplane; and

FIG. 6 is a three-quarter front perspective view of the airplane, taken from a position above the wing level.

The right and left sides of the airplane are substantially the same in appearance.

I claim:

The ornamental design for a twin tandem engine airplane, substantially as shown and described.
